DESIGN FOR A PAIR OF GOGGLES

Arthur W. Wilson, Riverton, N. J., assignor to
Bachmann Bros., Inc., Philadelphia, Pa., a cor-
poration of Pennsylvania

Application February 25, 1947, Serial No. 137,168

Term of patent 14 years

(Cl. D57—1)

To all whom it may concern:

Be it known that I, Arthur W. Wilson, a citizen
of the United States, residing at Riverton, in the
county of Burlington and State of New Jersey,
have invented a new, original, and ornamental
Design for a Pair of Goggles, of which the fol-
lowing is a specification, reference being had to
the accompanying drawing, forming a part there-
of, in which

Figure 1 is a front elevational view of a pair of
goggles showing my new design;

Figure 2 is a top plan view thereof; and

Figure 3 is a side elevational view of the same.

I claim:

The ornamental design for a pair of goggles, as
shown.

ARTHUR W. WILSON.
